ANTI-FREEZE-UP PROTECTOR FOR DOOR-HANDLE LOCK

Karl Meier, Wolfsburg, Germany, assignor to Kamei-Auto-Komfort-Wolfsburg Karl Meier KG., Wolfsburg, Germany, a corporation of Germany

Filed Jan. 27, 1967, Ser. No. 5,753

Term of patent 14 years

(Cl. D10—8)

Fig. 3

Fig. 2

Fig. 1

FIG. 1 is a plan view, as taken from either front or rear, of an anti-freeze-up protector for door-handle lock, showing my new design, the fastener being omitted for convenience of illustration;

FIG. 2 is a top plan view thereof, assembled; and
FIG. 3 is a front elevation thereof.

The elements shown in broken lines are included for illustrative purposes only.

I claim:

The ornamental design for an anti-freeze-up protector for door-handle lock, as shown and described.
